UNITED STATES PATENT OFFICE.

THOMAS H. FARRELL, OF FORT COLLINS, COLORADO.

ANTIWASHING CONSTRUCTION FOR ROADS.

1,420,535.

Specification of Letters Patent. Patented June 20, 1922.

Application filed November 18, 1920. Serial No. 424,883.

To all whom it may concern:

Be it known that I, THOMAS H. FARRELL, a citizen of the United States, residing at Fort Collins, in the county of Larimer and State of Colorado, have invented a new and useful Antiwashing Construction for Roads, of which the following is a specification.

This invention has reference to anti-washing construction for roads and its object is 10 to provide an arrangement for installation in roadways whereby the formation of gulleys or washouts is avoided, especially on hills.

In dirt roads or roads having a surfacing 15 where water may flow along the road surface with considerable force and in considerable quantities, which conditions may occur in hilly country particularly, there is a liability of gulleys or ditches forming during a rain storm or whenever water flows 20 down the hill, and such gulleys may enlarge until the road surface becomes difficult of travel or the gulleys may form to such depth as to make travel dangerous or render the 25 roadway impassable, particularly to automobiles and under certain conditions to horse-drawn vehicles.

In accordance with the invention retarding devices are provided to be installed in 30 the road surface at frequent intervals and in the path of water flowing by gravity down the hill, the retarding devices being, in some instances, provided with gutter forms at the sides and also provided with 35 gutter forms of shallow depth extending crosswise of the roadway and preferably trending angularly, with relation to the width of the road, in a down hill direction.

The gutter side of the retarding devices, 40 in their installed position, is arranged on that side of the road toward higher ground and the gutters are so arranged as to direct the water or the major portion thereof, across the roadway to the side toward lower 45 ground to divert the water away from the roadway so that no washing streams of water may be formed. In this way the production of ruts or gulleys is avoided since the retarding devices are so made as to resist wear, 50 and increasing volumes of water along fixed paths are prevented.

The retarding devices may be made of cement and are sunk in the roadways sufficiently to provide approaches preventing 55 destructive wear, while the cross gutters

are made shallow and of gentle slope to prevent jar to vehicles.

The invention will be best understood from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claims.

In the drawing:

Fig. 1 is a longitudinal vertical section of the roadway where provided with a retarding device.

Fig. 2 is a plan view of the arrangement shown in Fig. 1.

Fig. 3 is a perspective view of one of the retarding devices removed from the roadway.

Fig. 4 is a plan view of one of the retarding devices where the cross gutter is at an angle to the line of travel and to a direction crosswise of the roadway.

Fig. 5 is a section crosswise of the roadway indicating a crown form thereof.

Fig. 6 is a plan view of a modified form of the invention.

Fig. 7 is a longitudinal section of Fig. 6, like that of Fig. 1.

Fig. 8 is an elevation of Fig. 6 as seen from the left-hand end.

Referring to the drawing, Figs. 1, 2 and 3, there is shown a roadway 1 which may be considered as extending down hill from the left hand end to the right hand end, as viewed in Figs. 1 and 2. In hilly or mountainous regions, roadways are frequently formed on the sides of hills slanting crosswise of the roadway as well as lengthwise thereof, and in such cases the roadway may have a high side 2 and a low side 3 and between these two sides the roadway is frequently crowned, although the crowning may be omitted.

Sunken for a distance into the roadway 1 is a block 4 of suitable material, such as cement. This block may be formed of one or more pieces and is of generally rectangular shape in outline, sloping from ends 5 and 6 toward a central part where the block is provided with a transversed gutter, either 110

extending straight across, as best shown in Figs. 2 and 3, where the gutter is indicated at 7 or having the gutter diagonally arranged as indicated at 8 in Fig. 4. Along 5 that side of the block rising transversely of the hill as distinguished from the length of the hill is an up and down gutter 9 having the up-hill end low and rising therefrom toward a high point 10 of the block 4 where 10 the rise of the gutter 9 stops at a lower level than the high point 10 and then gradually drops, as indicated at 11, to the low end of the block 4. The high point of the longitudinal gutter, which high point is indicated at 12, is as high or higher than the depression of the gutter 7 but lower than the high point 10 of the block 4, whereby, 15 water gravitating down the side gutter 9 is retarded by the rising end of such gutter 20 and on passing from the high point 12 of the gutter flows on down the hill with a portion of the water directed into the gutter 7 to pass across the roadway and finally escape on the laterally down hill side of the 25 block 4. In this manner water flowing down the roadway, on reaching the block 4, is materially retarded in its flow and a material portion of the water is diverted from the direct path down the roadway to 30 one side to escape on the low side of the road and be so spread as to do no harm to the roadway, while the water and wear resistant block 4 prevents the formation of ruts or 35 gulleys in the surface of the road.

40 The ends 5 and 6 of the block 4 taper sufficiently toward their outer portions to be well covered by the roadway surfacing encroaching on the block, which later is exposed only adjacent to the gutter 7 or 8 as 45 the case may be. The longitudinal gutter 9 may also be in part covered by the roadway whereby the block 4 is effectively anchored in place. On the side of the long gutter toward the adjacent bank of the road there is an up-standing shield 13 protecting the upper side of the road from wash or caving.

50 The approach 6 toward the gutter 7 is gradual and rises slightly above the gutter 7 to form an extended ridge 14 of such length and gentle slope in the direction of travel as to avoid any sudden jar to a vehicle. The ridge or high point 10 is also 55 relatively long and gradual in the direction of travel and may be rounded where it merges into the end 5 of the block 4 so that the gutter 7 has little or no noticeable effect upon a vehicle traveling upon the road.

60 The gutter 8 being diagonal of the line of travel, also has but little effect upon a passing vehicle but necessitates an elongation of the side of the block 4 over the side provided with the longitudinal gutter 9.

65 It frequently happens in a dirt road that the wheels of a vehicle will cause ruts 15,

as shown in Fig. 2, to be formed in the surface of the road. These ruts confine water flowing down the roadway to narrow paths with the result that the ruts deepen and widen and ultimately produce gulleys finally 70 becoming impassable to vehicles and often times causing the destruction of the roadway. By placing the blocks 4 at suitable intervals, they form with their gutters 7 or 8 substantially non-destructible riffles preventing the water flowing down the road from attaining considerable velocity and wholly prevent the formation of destructive or impassable conditions. The riffles distribute the water and are so formed as to 75 offer no material interference to the passage of the vehicles.

In Figs. 6, 7 and 8, the block 4 is replaced by another block 4^a formed with a diagonally located riffle rib 7^a, serving the purpose of the gutter 7 or 8 in Figs. 1 and 4. The gutter rib 7^a is arranged diagonally so that water reaching the up-hill end of the block 4^a will be diverted thereby toward the other side of the block and be retarded and 80 spread out in such manner as to avoid formation of ruts or gulleys, while at the same time, because of its shallowness the gutter rib 7^a and the diagonal placing of such rib, prevents any interference with the passage 85 of vehicles. The upper and lower ends of the block 4^a on opposite sides of the gutter rib 7^a taper in thickness to form surfaces 5^a, 6^a which may be covered by approaches 1^a (see Fig. 7) partially overlying the block 100 4^a so that the block is imbedded in the roadway to a sufficient depth.

To avoid under-washing of the blocks 4 or 4^a as the case may be, the corners of these blocks are furnished with guards 16 105 diverting running water which may reach the blocks from undermining the corners of the blocks. The guards need be but about 3 inches in width and rise from the blocks above the surface of the ground at the sides 110 of the blocks for a distance of about 2 inches, more or less. These guards 16 extend up and down the roadway for a short distance and on the gutter side of the block 4. In the showing of Figs. 1, 2 and 3, these guards 115 do not encroach upon the gutter 9, but merge into the body of the guard with the high portion of the guard stopping short on the high portion of the block so as to leave the passageway 17 for the flow 120 of water crosswise of the roadway.

What is claimed is:

1. In road construction, a riffle block for insertion in the roadway, said block being of a length and width to extend along the 125 roadway in the line of travel and across the roadway from substantially side to side of the traveled surface thereof, said riffle block having water-diverting means extending in a continuous manner from side to 130

side of the roadway with said means of a depth and sufficiently extended to offer no material impediment to the travel of the vehicle along the line of travel.

- 5 2. In road construction, a riffle block resistant to wear of water flowing along the road and provided with water-diverting means extending in a continuous manner crosswise of the roadway, the diverting 10 means slanting from one side of the roadway toward the other and at a lower level at one end than at the other end whereby water is caused to flow crosswise of the roadway with a downward trend.
- 15 3. In road construction, a riffle block of a length and width to extend from one side of the road to the other across the line of travel and to extend in the direction of the line of travel, the riffle block having water- 20 diverting means extending crosswise of the road surface and the block being provided with gradually tapering ends to be covered by the surfacing of the roadway with the water-diverting means rising above the 25 roadway.
4. In road construction, a riffle block of a length and width to extend from one side of the road to the other across the line of travel and to extend in the direction of 30 the line of travel, the riffle block having an

elevated water-diverting means extending crosswise of the road surface and also provided with taper ends to be covered by the surfacing of the roadway, said riffle block also having a lengthwise gutter at one side 35 of the roadway rising from the receiving end and discharging against the crosswise water-diverting means.

5. In road construction, a riffle block for insertion in the roadway, said block being 40 of a length and width to extend along the roadway in the line of travel and across the roadway from substantially side to side of the traveled surface thereof, said riffle block having a water-diverting means ex- 45 tends diagonally across the block from a high point on one side to a low point on the other, and of an elevation and extent to offer no material impediment to the passage of the vehicle along the line of travel, 50 and the block at corner portions, provided with guards extending lengthwise of the blocks and rising above the road surface to an extent to prevent under washing of the block at the corners. 55

In testimony, that I claim the foregoing as my own, I have hereto affixed my signature.

THOMAS H. FARRELL.
